HONING DEVICE

Joseph Sunnen, Clayton, Mo.

Application October 22, 1942, Serial No. 462,952

11 Claims. (Cl. 51—184.3)

The main object of this invention is to construct a honing arbor or mandrel with means for substantially eliminating the possibility of vibration or chattering during the honing operation, whereby greater perfection is obtained in the finished surface.

Another object resides in the provision of a removable bearing shoe for the honing arbor or mandrel so constructed and arranged as to protect the body of the hone or mandrel against wear due to contact with the work and to provide means whereby an adjustment of the bearing shoe can be made to compensate for wear or to permit the use of the hone or arbor with work of different diameter.

Inasmuch as the coefficient of friction of an abrasive stone in operative engagement with its work is greater than that of a corresponding wear plate in engagement with the same work, it is essential that the abrasive stone and wear or bearing faces be arranged circumferentially of a mandrel in a predetermined manner to compensate for this differential. It is therefore an object of the present invention to so locate the wear or bearing shoe circumferentially on the mandrel and with respect to the hone face as to duly compensate for this difference in the coefficient of friction whereby maximum efficiency in the uniform distribution of radial forces is obtained to increase accuracy and eliminate undesirable vibration.

A further object of the invention comprehends the use of means for positively seating certain engaging surfaces between the wear plate and the hone, so as to eliminate the possibility of misalignment between these parts.

Other objects reside in the arrangement of the removable wear plate which is so constructed and arranged as to be laterally offset from an axial plane extending medially through the abrading surface, the offset being opposed to the direction of the load created by the engagement of the rotating abrading surface with the work, and being in direct proportion to the area of the abrading surface in working engagement and the friction present by virtue of the thrust between the abrading surface and the work; to secure the wear plate with at least one of its surfaces biased into engagement with the hone body and to make provision for eliminating all lost motion between the hone or the hone sections and it or their manipulative parts.

Other objects will more clearly hereinafter appear by reference to the accompanying drawings and claims forming a part of this specification,

and wherein like characters of references designate corresponding parts throughout the several views, in which:

45 The mandrel or arbor body is shown in the present illustration as being of cylindrical form, the length and diameter being determined by the nature of the work for which the assembly is designed. As in my Patent No. 2,350,969, the body of the device is formed at one end at 2 with the usual head portion which is inserted in the chuck end of the spindle of a machine of any suitable type, such as illustrated in my former Patent No. 2,070,381. A longitudinal recess 3 is formed throughout the length of the

arbor body, and this recess is designed to receive the hone elements 4, stop members 5 and 6, and the adjusting bar 7.

The adjusting bar shown in Figures 17 and 18 is particularly designed to cooperate with a hone assembly formed of two sections, although by a slight modification, the invention may be adapted for use where more or less than two hone sections are desirable. Because of the advisability of providing as compact a structure as possible, and in order to eliminate undesirable vibration due to lost motion, the slot or recess in the hone body is preferably formed relatively small with respect to the body structure. This also insures a rigidity of the body structure tending to eliminate any distortions which might otherwise be present. The slot or recess formed in the working body is of uniform depth with the sides parallel; however at the chuck end the slot is slightly restricted for a portion of its length as indicated at 8 with the bottom surface of the reduced end curved upwardly. The bottom of the slot at the chuck end of the arbor body curves downwardly at 9, and these variations in this end of the structure are for the purpose of facilitating the movement of the parts cooperating therewith.

As shown in Figure 3, there is positioned in the hone receiving recess, defined by side walls 10 and 11 and bottom wall 12, the operating bar 7, the outer stop member 5, and the inner stop member 6, together with the interengaging hone sections 4. The actuating bar 7 is best illustrated in Figures 17 and 18, this bar includes the offset shank portion 17 which is formed with the end hook or coupling member 18 by means of the recess 19. The upper surface of the bar 7 is notched at 20 to provide end walls 21 to cooperate with a suitable stop to limit the rectilinear movement of the bar and thus define the limits of movement and the radial adjustment of the hone. The offset portion 17 forming the inner shank of the actuating bar 7 is provided for the purpose of centralizing the forces of the control mechanism in their adjustment of the hone section. In that form of the invention shown in Figs. 1 to 17, inclusive, there is illustrated two sets of parallel, angularly extending guide slots 22, which extend entirely across the inner side face of the bar, these slots extending upwardly to the upper marginal edge of the bar to provide movement of the hones to a maximum extent, as determined by their pitch and the vertical height of the wall. It will be noted that by having the guide slots extending entirely across the inner face of the bar 7, maximum movement of the cooperating hones is essentially present.

The hones are illustrated as being assembled in sections, each section including a base to which a honing surface 23 is adhesively secured. The ends of each hone section are formed with recesses 24 defining hooks 25 so that the various sections which may be utilized can be interengaged for the purpose of creating a hone unit. The outer faces of the hones are formed with angularly extending projections 26 which extend in a direction complementary to the grooves 22 of the adjusting bar 7 and are adapted to seat and slide therein, this cooperation producing the radial movement of the hones in question. This structure is best illustrated in my Patent No. 2,350,969.

At the outer end of the assembly the stop 5 is positioned, this stop being illustrated in de-

tail in Figures 10, 11 and 12 and being constructed in a manner to permit its use as a stop element at the inner end of the assembly, between the hone elements and the mandrel body. The stop 5 is in the form of a plate, the thickness of which corresponds to the thickness of the hone elements. At the upper edge of the stop structure, is formed the overhanging lip 27 which overlies the upper edge of the actuating bar 7 to prevent radial movement of the latter. The lip 27 is of a width to substantially overlie the entire upper edge of the bar 7, thus insuring alignment of the latter during its movement. The inner end of the stop 5 is provided with a groove 28 forming the hooked extremity 29 for interengagement with the hook 25 of the adjacent end of the hone 4. The hook 29 does not extend the full height of the stop, but terminates medially of its height to provide a shoulder 30 upon which the shoulder 31 of the hone seats, when the hone is wholly retracted. The interengaging hook 29 of the stop 5 with the outer hook 25 of the hone element 4 limiting rectilinear movement, but providing for guided vertical movement of the hone part. A threaded opening 32 in the stop 5 is to be aligned with the opening 33 in the arbor body to receive a screw 34 to lock the parts together. The outer end of the stop 5 has the hook 106 extending the full height of the plate structure to permit its use in a manner hereinafter described.

The inner stop 6 includes a flat plate, shown to be of rectangular form, this plate having a smooth outer surface which abuts against the adjacent face 10 of the mandrel 7. This stop 6 is formed with inwardly projecting ribs 35, 36 and 37 which define a pocket having an open outer end face and in which is formed a boss 38, located centrally of the pocket and confined thereby. The thickness of the stop structure through the boss and the ribs is substantially identical with the thickness of the hone. To the boss 38 is fixed a coiled spring 39 having an upper surface engaging the inner face of the upper rib 35 and a portion engaging the upper face of the lower rib 37 to stabilize the spring movement. The free end of the spring 39 extends outwardly beyond the rib 35 and is bent downwardly to provide a vertical end portion 40 which is adapted to abut the inner end of the adjacent hone section. It will be noted that the vertical end 40 of the spring is substantially spaced inward of the outer edge 41 of the stop 6, so that the abutting end 42 of the adjacent hone will have a side surface area against which the hone can travel to the full extent of its movement. An overhanging lip 44 extends laterally at the upper outer edge of the stop 6 to overlie and engage the upper face of the actuating bar to confine the latter against vertical movement. The boss 38 is formed with a central threaded opening 45 which is adapted to be aligned with the opening 46 in the side wall of the arbor body for the reception of a screw 47 to secure the stop against movement. The inner faces of the ribs 35, 36 and 37 are flush with the inner edges of the hone elements 4 and the inner face of the outer stop 5, and the thickness of these parts, plus the thickness of the actuating bar 14, comprehend a measurement of such a character that when assembled between the vertical faces 10 and 11 of the slot 3 of the arbor, there will be just sufficient clearance to permit relative movement between the parts.

In using a honing mandrel or arbor of the present type, it is inserted within the confines of the

cylindrical wall which is to be honed. The honing elements are expanded a predetermined distance representing the amount of surface to be removed. To provide for this honing movement, it is essential that the hone engage the inner wall of the surface being operated upon at points opposed to that represented by the hone elements. These points of contact between the hone body and the working surface constitute a bearing which is subject to wear, and, therefore, subject to modification to compensate for the wear. As one of the features of the present invention, it is contemplated that the wearing surfaces of the arbor shall be so positioned with respect to the honing surfaces that they will receive the movement or thrust from the honing operation at a medial point so that the wear of the bearing faces will be uniformly distributed and so that any lateral vibration which might result from an improper alignment of the bearing faces will be compensated for and a more perfect face produced by the honing operation.

The foregoing is accomplished in the present instance by providing bearing or wear shoes which are detachably fixed to the mandrel body to permit an interchange of this part and adjustment to accommodate wear, the location of the bearing shoes being so determined that the forces created by engagement of the hone with the work will be evenly dispersed throughout the bearing area.

The mandrel body in the present illustration is formed with longitudinally extending circumferentially spaced shoulders 50 and 51 for the reception of the bearing shoe or wear plate (Figures 13 to 16, inclusive), the latter being provided with arcuate bearing faces 53 so disposed that a radial plane extending medially of the same and axially of the mandrel will intersect at all times a radial plane extending axially of the fixed center of rotation of the mandrel and intersecting the working surfaces of the hone elements 4. The present mandrel is mounted with a fixed center of rotation, the working center shifting with the wear of the bearing shoes and the radial movement of the hone elements.

It will be noticed from Figure 6 that a vertical plane extending axially of the mandrel body does not bisect the hone receiving recess, the latter being slightly offset to assist in the distribution of the force developed by the frictional engagement of the hones with the work, and it will be apparent that the coefficient of friction between the hone and the work will be a variable factor which may slightly alter the disposal of the bearing faces with respect to the plane of the working face of the hone elements. The speed of rotation, type of abrasive material, pressure between the work and the honing surface and other factors may also enter into the relative arrangement of the various parts.

The bearing shoes include the parallel legs 54 formed with the spaced seating surfaces 55 which in assembly abut the shoulders 50 of the mandrel body. It is intended that adjustment of the bearing shoes to compensate for wear or to permit the use of the mandrel in work of varied diameter be accomplished by the use of shims 56 (Fig. 23) interposed between the shoes and the mandrel and this adjustment or the substitution of new shoes is facilitated by the use of the fasteners 57 of which several are shown in each shoe section. The fasteners 57 are illustrated as screws which extend through the shoes and into the mandrel body and in this connection it has been found that a more positive and

desirable seating of the parts may be obtained by a slight offset of the shoe opening with respect to the mandrel opening, say .010 of an inch to jam opposed surfaces together. This is shown best in Figs. 5 and 6 in which figures the opening 58 is offset with respect to the opening 59 in the mandrel so that the screw 57 urges the abutting face 59' of the bearing shoe against the face 60 of the mandrel. To prevent displacement of the wear plates or bearing members the mandrel is formed with a plurality of equally spaced projections 61 along its under surface and intermediate the shoulders 50. These projections 61 seat in depressions 62 defined by the transverse ribs 63 in the inner concave faces of the bearing shoes. It will be noted that the end ribs 63' of each shoe are only one half as thick as the intermediate ribs so that in assembly abutting end ribs of a pair of shoes will snugly seat between a pair of projections 61. The screw openings for fastening the shoes to the mandrel extend through the projections 61 and thus a more substantial connection is possible. The bearing shoes are recessed lengthwise, intermediate the bearing portions 53 to accommodate the head of the fastening elements and to limit the area of the bearing surfaces. The bearing area is further limited by suitable transverse slots 64 which inherently increase the radiating surface of the wear parts. The number of wear shoes used on each mandrel may not be of great importance except to permit quick adjustment or interchange of parts or to reduce the expense of replacement. The position of the shoe on the mandrel is important, however, in that it insures a greatly improved finished surface.

It will be noted in Figure 8 that the mandrel is formed with screw opening 33 in the base of the hone recess to permit the use of vertical screw in fastening the stop 5 in position. The screw opening 33' is to receive a vertical screw when the end stop 5 is converted to use as an inner stop as shown in Figures 19 and 20, although in these figures the arrangement of the fastening screw is shifted to extend transversely of the hone recess to illustrate a variation in this connection.

My invention is adapted to numerous uses, and one of the features thereof is a provision of a substitute cam and hone arrangement which makes the device particularly adapted to the grinding of holes for a blind end. One of the problems in finishing holes of the type, which have one end closed or blind, is to provide for the adjustment of the hone without having the cam project beyond the end of the arbor, which would, of course, prevent the hone from extending to the full depth of the hole.

It will be understood that the machines in which these hones are operated is of the type shown in my copending application, Serial No. 427,655, or my Patent No. 2,070,381. In these machines, the expansion of the hone arbor is produced in two stages, the first being a comparatively rapid expansion to the point which is preset at the start of the honing operation to correspond to the point at which the honing begins to take effect, and the second stage is a slow feeding of the hone into the work through the honing operation. These two movements are highly desirable for general honing, because the hone can be contracted so as to easily clear the hole to permit the placing of the work in position on the hone arbor and then are expanded quickly to the position at which the hone starts

work, after which the hone is slowly fed through the cutting operation. This involves a comparatively long travel of the cam bar, and, of course, the hones must follow when the cam bar is withdrawn to contract the hones. This long travel of the cam bar makes it impractical to use the standard cam bar for honing holes having a blind end through which the cam bar cannot project where the end of the hones must project to the bottom of the hole.

A further feature of my invention is the provision of the cam shown in Figures 21 and 22 which is used in conjunction with hones having projecting lugs at the proper angles, and these hones are made in such a manner as to permit the withdrawal of the cam bar a substantial distance without further contraction of the hone after it has reached the bottom of the slot. To this end, I provide the cam bar shown in Figures 21 and 22 with a slot 100 into which the lug 101 of the hone can project after it has been drawn down below the end of the cam track 102, it being understood that the cam track 102 is parallel to a corresponding track 103, and a notch 104 at the end of the cam bar corresponds to the slot 100. The movement of the cam bar during the rapid travel part of the stroke does not produce any expansion of the hone due to the fact that the lugs of the hone are in the slots 100 and 104 and are not required to move due to the fact that these slots are parallel to the axis of the cam bar. However, during the slow feeding part of the travel of the cam bar, the lost motion, due to the slot 100 and the notch 104, has been taken up, and the feeding of the hone takes place. In other words, the cam bar is withdrawn substantially backward from the blind end of the hole during the rapid travel portion of its stroke.

When it is desired to hone holes which have a closed end, it is desirable to shift the stop 5 away from the end of the arbor which would otherwise prevent the positioning of the hone at the end of the arbor. For this reason, I provide the stop 5 with a slot and hook arrangement 105-106 corresponding to the slot and hook arrangement 28-30, and I provide holes in the central part of the arbor to receive the screw which passes thru the hole 32. I also provide the hones with what might be called a car pulley type of engaging means at each end to engage the grooves 28 or 105 selectively, according to whether the hone is to be used to finish a blind end hole or an open end hole.

It will be understood, of course, that where the hone is mounted at the extreme end of the arbor, it will be necessary to omit the stop 6, in which case, however, any lost motion in the slot 28 might be taken up by the provision of special means.

From the foregoing it will be observed that the novel construction of the honing arbor heretofore disclosed provides a mechanism extremely compact in assembly, accurate in adjustment and involving features which eliminate the possibility of vibration during use. This structure reduces to a minimum wear of the parts, permits adjustment or substitution of additional or new bearing faces and in the modified form permits the honing of a dead end hole to its full depth.

The preferred manner of using the instant invention is in connection with the honing machine of application Serial No. 427,655 or the honing machine of my Patent No. 2,070,381, although it will be apparent to one skilled in the art that the present structure could be utilized in other ma-

chines of the same general character, providing that these latter machines incorporate in their assembly the essential adjusting and operating mechanism. Both of the modifications incorporate in principle some of the main features of the present development, including the construction and arrangement of the bearing shoe with respect to the hone and the various devices for fastening the parts together in order to permit as complete an interchange as practical. In other words, the arbor body is so constructed that the hone elements can be secured for proper adjustment either for normal pin hole grinding or for the grinding of dead end holes. Where dead end holes are to be honed a modified form of actuating bar is utilized, this actuating bar including notches for the purpose of giving a certain amount of lost play to the hones so that upon initial operation of the machine, which is rapid, there will be substantially no hone response, the hone response being gradual and relatively slow because of the nature of the operation and lack of ability to observe the actual honing operation.

The shape of the cam or cam faces of the actuating bar may vary in different instances, it being preferred that the cam face or faces be in the form of grooves in the bar to cooperate with projections provided on the body structure of the hone elements. This preferred form enables a more compact assembly and insures more accurate relative movement of the parts. The direction of inclination of the cam faces is best determined by the direction of movement of the operating member of the grinding machine to which the arbor is operably connected.

If the operating member of the honing machine moves outwardly from the arbor assembly then the cam faces must be inclined properly to radially move the hone elements outwardly in response to the outward movement of the operating member, and the reverse is likewise true.

Various details of construction can be modified without departing from the spirit of the invention.

I claim:

1. A pin hole grinding device including an arbor having a longitudinally extending slot for receiving honing elements, a hone in said slot, a removable bearing element located on the outer face of the arbor in a position opposed to said hone, means for fixing said bearing element in the desired position with respect to the center of the arbor to permit the use of said arbor in holes of the desired diameter, and means diagonally wedging the bearing elements into seating engagement with said arbor.

2. A pin hole grinding device including an arbor having a longitudinally extending slot, a honing element in said slot, a stop to limit the longitudinal movement of said hone in one direction, a stop limiting the movement of the hone in the other direction, and removable resilient means interposed between one of said stops and said hone.

3. A pin hole grinding device including an arbor having a longitudinally extending slot, a honing element in said slot, means for adjusting the honing element radially, outer and inner stop members at each end of said honing element, resilient means interposed between the inner stop and said honing element, circumferentially spaced removable bearing elements located on the outer face of said arbor opposite to its direction of rotation, and means comprising a spacing element for fixing the radial position of said bear-

ing elements to permit the use of said arbor in holes of the desired diameter.

4. A honing arbor for use in internal grinding, said arbor including a longitudinally extending hone receiving groove, a removable wear plate for said body constructed and arranged to uniformly receive the thrust created by the honing operation, and means for securing the wear plate to the body, said means being biased to urge said wear plate against said body in a direction opposed to the direction of movement of said arbor.

5. In a honing mandrel for use in internal grinding including a body formed with an elongated recess for receiving radially expansible honing elements, a slideable actuating bar for said honing elements, means for securing the actuating bar against radial movement, means at the outer end of the recess for securing the honing elements against longitudinal movement in one direction, and a stop in said recess and spaced inwardly of the inner end of said honing members, and spring means interposed between said stop and said honing members for retaining the honing members in compact relation.

6. A honing mandrel for use in internal grinding including a body formed with an elongated recess for receiving radially expansible honing elements, longitudinally extending shoulders formed on the body of said mandrel, said shoulders being circumferentially spaced unevenly with respect to the recess, a bearing shoe of arcuate form having its longitudinal marginal edge portions seating on said shoulders, and fastening means for said mandrel, said fastening means urging said mandrel laterally to bias the engagement of contacting faces of the mandrel and bearing shoe.

7. A grinding arbor for use in grinding dead end holes including a body having a longitudinal recess extending to its outer end, a honing element in said recess having the outer extremity of its honing surface flush with the outer end of said arbor, an actuating element arranged for rectilinear movement in said recess adjacent said honing element, said actuating element including cam faces for cooperating with projections provided on said honing element, and means for retarding the initial movement of said hone upon movement of said actuating bar.

8. A grinding arbor for use in grinding dead end holes including a body having a longitudinal recess extending to its outer end, a honing element in said recess having the outer extremity

of its honing surface flush with the outer end of said arbor, an actuating element arranged for rectilinear movement in said recess adjacent said honing element, said actuating element including cam faces for cooperation with portions of the honing element and being so constructed and arranged that the initial movement of the actuating member will result in only a restricted movement of said hone.

10 9. A grinding arbor for use in grinding dead end holes including a body having a longitudinal recess extending to its outer end, a honing element in said recess having the outer extremity of its honing surface flush with the outer end of said arbor, an actuating element arranged for rectilinear movement in said recess adjacent said honing element, said actuating element including a cam face for cooperating with a portion of the honing element and the cam face being interrupted with a recess for varying the camming action to provide for discontinuation of the hone movement at a predetermined point in its travel.

15 10. A grinding arbor for use in grinding dead end holes including a body having a longitudinal recess extending to its outer end, a honing element in said recess having the outer extremity of its honing surface flush with the outer end of said arbor, said honing elements including projecting portions, an actuating element arranged for rectilinear movement in said recess adjacent said honing element, said actuating element including an inclined cam face for cooperation with the projecting portions of the honing element, said inclined cam face being interrupted to provide a delay in the hone movement upon initial movement of said actuating element, means for securing said honing element against rectilinear movement, and means for securing the actuating element against radial movement.

20 11. A wear shoe for hone arbors comprising a channel shaped body, having longitudinally extending marginal edge portions and symmetrical ends, substantially parallel inner walls forming a channel between said edge portions, cross braces extending across said channel and connecting said walls, openings formed in said wear shoe adapted to receive fasteners, said cross braces and openings being symmetrically spaced with respect to the ends of said wear shoe, whereby said shoe may be reversibly positioned without changing the location of the fasteners.

JOSEPH SUNNEN.
